UNITED STATES PATENT OFFICE

2,422,469

ELECTRON EMITTING CATHODE

Edward A. Coomes, Cambridge, Mass., assignor,
by mesne assignments, to the United States of
America, as represented by the Secretary of
War

Application July 9, 1945, Serial No. 604,012

1 Claim. (Cl. 250—27.5)

1 My invention relates in general to thermionic tube structure and more particularly to an improved form of cathode therefor.

In apparatus such as radio object-locating apparatus it is necessary that pulses of extremely large instantaneous power and short duration be developed and due to the voltage used and the currents involved, the life of tubes used in this type of apparatus has not been nearly as long as desirable, mainly because of the effective life of the cathode thereof. Accordingly, it is one of the main objects of my invention to provide a thermionic cathode which is particularly adaptable for use in this general type of tube and which will have a long life.

The pulses hereinafter referred to necessitate a high primary emission from the cathode when such a tube is working under pulsed conditions. Therefore, it is another of the objects of my invention to provide a cathode which when used in tubes of this nature, will give a high primary emission.

Since the values of current involved are large, comparatively speaking, and since voltages involved are considerable, it has been noted in the past that a certain amount of sparking will take place at the cathode and it is desirable that this sparking be minimized or if it occurs at all that the value of the current emitted by the cathode be as large as possible before this phenomenon takes place. It is, therefore, another of the objects of my invention to provide a cathode in which an increased value of current will be provided before sparking takes place as compared to those cathodes which have been utilized previously.

My invention will best be understood by reference to the drawings, in which:

Fig. 1 illustrates one embodiment thereof; and

Fig. 2 shows a modified form of the invention.

Referring to Fig. 1, there is shown a preferable form of cathode structure in accordance with my invention. In this figure a nickel sleeve 10 has placed there around a nickel wire mesh 15 which has been continuously welded or sintered thereto. The interstices of the mesh are filled with a precipitated double salt which is $\text{BaSr}(\text{CO}_3)_4$. This salt then is broken down to the oxide by heating and it is the oxide of the salt that is used as the emitting material. Care is taken that the emitting material is not made thick enough to actually cover the wire mesh but is just thick

enough to fill in the gaps of the wire mesh. This results not only in an improved emitting material but also results in a very good heat distribution throughout the emitting material and hence the thermal conductivity can be maintained substantially constant and the advantages of the described structure can be maximized.

Referring to Fig. 2, there is shown a cross-section of the structure with the usual type of heating filament and attendant insulating blocks used. In this figure, the nickel sleeve 10 holds the mesh 15 with the emitting oxide held in close contact thereto and each end of the sleeve contains an apertured insulating block 20 and through which is passed the leads to the heater element 25. The heater element is energized by a filament voltage from a source not shown, but indicated.

It will be obvious to those skilled in the art that there may be departures from the particular showing herein which will fall fairly within the spirit and scope of the invention and accordingly I claim all such departures as fall within the purview of the hereinafter appended claim.

25 What I claim is:

A cathode comprising a metallic, unperforated tube, an uncoated metallic mesh surrounding the tube and metallically integrated therewith and comprising straight wires disposed at right angles to define rectangular spaces around the tube, electron emissive material at the bottom of each space and in contact with the metallic tube and the wires, the latter extending exposed beyond the outer surfaces of the electron-emissive material.

EDWARD A. COOMES.
